UNITED STATES PATENT OFFICE.

EDWIN H. BRODEN, OF RANKIN, PENNSYLVANIA, ASSIGNOR TO THE AMERICAN STEEL
AND WIRE COMPANY OF NEW JERSEY, A CORPORATION OF NEW JERSEY.

NAIL MACHINE.

Application filed November 3, 1921. Serial No. 512,587.

To all whom it may concern:

Be it known that I, EDWIN H. BRODEN, a citizen of the United States, and resident of Rankin, in the county of Allegheny and State 5 of Pennsylvania, have invented certain new and useful Improvements in Nail Machines, of which the following is a specification.

This invention relates to nail machines, and more particularly to wire nail machines, 10 and has for one of its objects the provision of a double-blow machine adapted to form the head of the nail in two separate operations.

Another object is to provide an improved 15 machine of this class that will produce an improved form of nail.

A further object is to provide a machine that may be operated at a high speed, will be simple in construction, durable, and a 20 general improvement in the art.

The above and other objects and advantages will be more fully brought out in the following specification and illustrated in the accompanying drawings, in which—

25 Figure 1 is a side elevation of the machine.

Figure 2 is a top plan view thereof.

Figure 3 is a side elevation of the opposite side from that of Figure 1.

Figure 4 is a longitudinal vertical sec- 30 tional elevation.

Figure 5 is an enlarged detail top plan of the cross-head and hammer stock holder.

Figure 6 is an enlarged sectional elevation 35 of the cross-head and hammer stock holder.

Figure 7 is a sectional elevation on the line VII—VII of Figure 2.

Figure 8 is an enlarged detail of the double blow mechanism.

Referring more particularly to the drawings the numeral 2 designates the frame of 40 the machine which is preferably formed of a single casting so as to provide the strength necessary to withstand the heavy vibration and shocks to which the machine is subjected.

45 A main drive shaft 3 is journaled in suitable bearings in the rear of the frame 2 and is provided at one end with a flywheel 4 and loose and fixed drive pulleys 5 and 6 respectively.

The opposite end of the shaft 3 is provided 50 with a gear 7 which meshes with a gear 8 on a shaft 9. The gear 7 is one-half the size of the gear 8 so that the shaft 3 will rotate just twice as fast as the shaft 9, this gear

ratio of two to one being necessary for a purpose to be hereinafter brought out.

The shaft 3 is offset adjacent its center to form a crank portion 10 which carries a pitman 11 which has its other end pivotally secured to a hammer cross-head 12. The cross-head 12 is supported and adapted to have a sliding movement on a pair of guideways 13 and 14 formed on the top of the frame 2.

A hammer stock holder 15 is mounted in the cross-head 12 for vertical sliding movement and is provided with a hammer stock socket 16 adapted to receive upper and lower hammer stocks 17 and 18 carrying 70 hammers 17^a and 18^a, respectively. The hammer 18^a is provided with a frusto-conical recess 18^b in its face, the purpose of which will be brought out in the detail description of the operation of the machine. The stocks 17

75 and 18 are locked or secured in position by set screws 19 and 20, and adjusting wedges 21 and 22 are mounted in the hammer stock holder so as to engage the inclined rear end of the hammer stocks 17 and 18, respectively, 80 and are adapted to be threaded downwardly against, or upwardly away from the hammer stocks to adjust them inwardly or outwardly respectively, as may be desired.

The hammer stock holder 15 is mounted 85 for sliding movement on a carriage 24 which is in turn slidably mounted for vertical movement in a guideway 25 on the frame 2. The carriage 24 is provided with a T-shaped head 26 which is mounted in a correspondingly shaped slot 27 in the lower face of the hammer stock holder 15, so that the hammer stock holder is reciprocated vertically with the carriage 24.

The carriage 24 is normally held in its 90 lowermost position by a coil spring 28 which has one end secured by an eye-bolt 29 to a projection or lug 30 on the carriage and its other end secured by an eye-bolt 31 to the base of the frame 2.

The carriage 24 is adapted to be reciprocated vertically by a transverse rocking lever 32 which is connected intermediate its ends to the carriage by a link 33 and has one end pivotally fixed at 34 to the frame 2 and its other end pivotally connected to an adjustable link 35. The link 35 is pivoted to the lever 32 so as to have a movement parallel to the longitudinal axis of such lever. The other end of the link 35 is pivotally con- 105

ected to one end of a cam lever 36 which extends rearwardly at right angles to the lever 32. The link 35 is pivoted to the lever 36 so as to have a movement parallel to its longitudinal axis. The effect of the link 35 with its pivotal connections with the levers 32 and 36 is to form what may be called an adjustable universal connection between said levers.

10 The cam lever 36 is pivoted intermediate its ends to the side frame of the machine, and is provided adjacent its rear end with a roller 38 adapted to contact with a cam 39 on the shaft 9.

15 The cam 39 is adapted to ride on the roller 38 and rock the rear end of the lever 36 downwardly, thus lifting the forward end and the lever 32 so as to raise the carriage and hammer stock holder 15 against the tension of spring 28. The vertical movement of the carriage 24 and hammer stock holder is just sufficient to raise the lower hammer 18^a on a line with the lowest position of the upper hammer 17^a.

20 In other words, the lower hammer 18^a is raised so it will strike the same point that the upper hammer 17^a will strike when in its lowest position.

The hammer stock holder 15 carrying hammers 17^a and 18^a is adapted to be reciprocated horizontally or forward and backward by the pitman 11 which is connected to the cross-head 12 and the crank of the main drive shaft 3, and the carriage 24 is adapted to be reciprocated vertically or up 30 and down by the lever mechanism above described, which is operated by the cam 39 on the shaft 9. Therefore, since the shaft 9 is driven by the shaft 3 through a two to one gear connection, the pitman 11, cross-head 12, and hammer stock holder 15 will be reciprocated forward and backward to each up and each down movement of the carriage 24.

40 The horizontal and vertical reciprocatory movements above described are so timed that the carriage 24 and hammer stock holder 15 will move upwardly on each alternate back stroke of the pitman 11, and hammer stock holder, and downwardly on the other back strokes, thus changing the position of the hammers for each forward stroke of the pitman 11. The cam 39 is so shaped that the lever mechanism operated thereby will remain substantially stationary during 50 the forward strokes of the hammers.

45 A die block 42 is arranged forward of the hammer stock holder 15 and is adapted to receive the wire from which the nail is to be made. The wire is fed into the die block 42 by a suitable feed table 43 which is reciprocated to feed the wire by a connecting rod 44 having one end connected to a crank arm 45 on a rocker shaft 46 which is provided with a finger or pusher arm 47 55 adapted to strike and move the feed table

forwardly against the tension of springs 47^a as the shaft 46 is rocked forwardly, the springs 47^a serving to retract the feed table as the shaft 46 is rocked in the reverse direction.

70 The feeding head 43 is adapted to feed the wire through the die after each blow of the hammer 17^a which finishes the head of a nail, the movement being just sufficient to feed the wire through the length of 75 the nail.

80 A pair of cutters or knives 48 and 49 are provided in front of the die blocks 42 and adapted to cut the headed portion of the wire off in the usual manner at the termination of the feeding of the wire, forming a pointed finished nail. The cutters or knives 48 and 49 are adapted to be reciprocated by rocking arms 50 and 51, respectively, which are pivoted intermediate 85 their ends as at 52 and are adapted to be rocked by suitable cams 53 and 54, respectively, which are mounted on the shaft 9.

90 The detail operation of the machine is as follows—

95 The machine being set in operation, wire is fed through between the dies 42 by the feeding head 43, and the cutters 48 and 49 are operated to cut off the protruding end of wire to a predetermined length, leaving a sufficient length of wire protruding beyond the dies to form the head of a nail. The operation thus far described is the same as in the well known and approved 100 form of single-blow nail machines now in use.

105 During the above operation the carriage 24 has been moved upwardly so that the hammer 18^a is in position to strike the protruding end of the wire. The hammer 18^a will first strike the wire, and due to the frusto-conical recess 18^b in its face, will form or center the protruding end of wire into a cone-shaped head. The hammer stock holder will now be moved rearwardly 110 for a second blow and at the same time the carriage 24 will move downwardly to allow the hammer stock holder 15 to move down so that the flat faced hammer 17^a will be on a line with the cone-shaped head formed by the hammer 18^a. The hammer stock holder will now be forced forward 115 so as to cause the hammer 17^a to strike the cone-shaped head, thus flattening it and forming a round flat finished nail head such as ordinarily formed on roofing nails. However, due to the pre-forming or cone-shaping of the wire by the hammer 18^a more metal can be used to form the head 120 than is possible with the ordinary single-blow machines, and consequently a larger and stronger head is produced.

125 After the hammer 17^a has flattened the head, the hammer stock holder is moved rearwardly and the wire is fed through the 130

dies 42 by the feeding head 43 an amount equal to the length of the nail, and the cutters are then moved inwardly to cut off the headed portion of the wire and form the nail point, sufficient wire being left protruding to form the head of the next nail. Also while the hammer stock holder is being moved rearwardly, and the wire being fed through the dies and cut off, the carriage 24 is again moved upwardly so that when the hammer stock is again moved forwardly, the lower hammer 18^a is again in line with the end of wire projecting through the dies. The above cycle of operations is repeated continually while the machine is in operation.

This improved machine, as before stated, forms a stronger head of larger diameter than single-blow machines, and also permits the use of wire of a diameter equal to the diameter of the finished shank of the nail, since a greater length of wire may be used to form the head due to the novel two-blow forming thereof. Heretofore, when making large head nails, such as roofing nails, it has been necessary to use wire stock of a greater diameter than the diameter of the finished nail shank in order to have sufficient stock from which to make the head, since if too great a length of wire protruded beyond the dies the head would form irregular and ragged. Therefore, it was necessary to so form and operate the dies of the machine so that they would draw the wire forming the nail shank down to size. This drawing of the nail shank resulted in the forming of a weak shank nail that would bend and break when driven.

While I have shown and described only one preferred embodiment of my invention, I do not wish to be limited thereto, since various modifications in design and combination of parts may readily be made without departing from the spirit of my invention as defined in the appended claims.

I claim:—

1. A nail machine comprising in combination, a frame, a die for forming the nails, a feeding head adapted to feed suitable wire stock into said die, cutters for cutting off the wire after a head has been formed thereon, a pair of guideways in said frame, a cross-head slidably mounted for horizontal movement on said guideways, a carriage mounted for vertical movement in said frame, a hammer stock holder slidably mounted for vertical movement in said cross-head and for horizontal movement on said carriage, a pair of hammers mounted one above the other in said holder, one of said hammers being provided with a frusto-conical recess in its striking face, a crank drive shaft journaled in said frame, a pitman connected to said crank shaft and said cross-head adapted to reciprocate said cross-head

and holder horizontally backward and forward to cause said hammers to strike the wire in said die, thereby forming a nail head, and means for reciprocating said carriage and holder vertically so as to aline said recessed hammer with the wire in the die on each alternate forward stroke. 70

2. A nail machine comprising in combination, a frame, a die for forming the nails, a feeding head adapted to feed suitable wire stock into said die, cutters for cutting off the wire after a head has been formed thereon, a pair of guideways in said frame, a cross-head slidably mounted for horizontal movement on said guideways, a carriage mounted for vertical movement in said frame, a hammer stock holder slidably mounted for vertical movement in said cross-head and for horizontal movement on said carriage, a pair of hammers mounted one above the other in said holder, one of said hammers being provided with a frusto-conical recess in its striking face, a crank drive shaft journaled in said frame, a pitman connected to said crank shaft and said cross-head adapted to reciprocate said cross-head and holder horizontally backward and forward to cause said hammers to strike the wire in said die, thereby forming a nail head, a second shaft journaled in said frame, gearing connecting said shaft with said drive shaft, a cam on said second shaft, and lever mechanism connected to said carriage and operated by said cam for reciprocating said carriage and said holder vertically, said cam and lever mechanism being adapted to move said carriage and holder upwardly on each alternate backward stroke of said cross-head and holder and downward on the other backward stroke thereof, and said holder 100 and carriage being adapted to remain substantially vertically stationary during the forward strokes of said holder. 105

3. In a double blow nail machine, a hammer stock holder having a hammer stock 110 socket opening through the forward face thereof, a plurality of hammer stocks slidably mounted in said socket opening, and means for independently adjusting said hammer stocks in and out of said socket 115 opening.

4. In a double blow nail machine, a hammer stock holder having a hammer stock socket opening through the forward face thereof, a plurality of hammer stocks slidably mounted in said socket opening, and independent wedge members mounted in said hammer stock holder and adapted to be operated to adjust said hammer stocks in or out of said socket opening. 120

5. In a double blow nail machine, a hammer stock holder having a hammer stock socket opening through the forward face thereof, a plurality of hammer stocks slidably mounted in said socket opening, said 125

hammer stocks having their rear ends cut away forming inclined bearing faces and a plurality of wedge members mounted for vertical movement within said socket opening, one of said wedge members being provided for each of said hammer stocks, and each of said wedge members being in engage-

ment with the inclined rear end face of its respective hammer stock so that vertical movement of said wedge will cause a horizontal movement of said hammer stock. 10

In testimony whereof, I have hereunto signed my name.

EDWIN H. BRODEN.
